CARRIER WAVE SIGNALING SYSTEM

Charles Eric Strong and Francis Charles McLean,
London, England, assignors to International
Standard Electric Corporation, New York,
N. Y.

Application January 11, 1936, Serial No. 58,765
In Great Britain February 1, 1935

4 Claims. (Cl. 179—171)

This invention relates to carrier wave communication systems and particularly to radio telephone transmitters. It has for its object to reduce the primary power consumption of transmitters without degrading appreciably the standard of service afforded.

More specifically the invention aims at applying the variable carrier method of operation to radio transmitters in an improved manner.

10: In the accompanying drawings Fig. 1 shows schematically a known arrangement for operating with variable carrier whilst Figs. 2 and 3 illustrate two embodiments of our invention; and Fig. 4 illustrates another embodiment somewhat 15: similar to that of Fig. 3.

In a radio transmitter operating with variable carrier or, as it is sometimes called, floating carrier, a high frequency amplifier is modulated simultaneously with speech frequency voltages and 20: with syllable frequency voltage, that is a unidirectional voltage varying at syllable frequency in accordance with the mean amplitude level of the speech frequency currents. One method of accomplishing this, which is in use at the present time, is 25: shown in Fig. 1 in which 1 is a high frequency amplifier which is plate modulated by audio frequency and syllable frequency voltages; 2 is a bank of one or more modulator valves acting as a class A amplifier, the grids of which are excited by audio fre-

30: quency and syllable frequency voltages, 3 is a rectifier producing syllable frequency voltages by the rectification of the speech frequency currents, and 4 is a source of fixed high tension anode supply voltage. The voice frequency voltages on the 35: grids of the modulator valves are amplified in those valves and cause audio frequency currents to pass through the circuit comprising the plate to filament resistance of the modulated amplifier 1 and the by-passing condenser C₁, thus setting up 40: audio frequency voltages across the plate to filament resistance of the modulated amplifier and so modulating at speech frequency the high frequency output of that amplifier. Similarly, the syllable frequency excitation of the grids of the 45: modulator valves causes amplified syllable frequency currents to flow in the circuit comprising the plate to filament resistance of the modulated amplifier and the impedance presented by the high tension supply which is low for syllable frequencies, setting up syllable frequency voltages 50: across the plate to filament resistance of the modulated amplifier and so modulating the high frequency output at syllable frequency. The final result is that when audio frequency input is 55: absent, the high frequency output from the modu-

lated amplifier is a steady carrier the amplitude of which is determined by the value of high tension supply voltage. If a single tone audio input is now applied, the output from the syllable frequency rectifier is a D. C. voltage which when applied to the grids of the modulator results in a D. C. voltage across the modulated amplifier which, adding to the voltage of the high tension supply, causes the high frequency carrier amplitude to rise. At the same time the carrier is 10: modulated by the audio tone. If speech currents are applied, the carrier level fluctuates at syllable frequency corresponding to the rectified speech frequency input, and at the same time the fluctuating carrier is modulated by the speech frequencies. 15:

The system described above suffers from the disadvantage that the speech and syllable frequency modulator being a class A amplifier with a permanent polarising plate current is inherently 20: inefficient in respect of the ratio of the speech frequency and syllable frequency power output compared to the plate input supplied from the high tension source.

It is one object of the present invention to provide a means of applying floating carrier which is consistent with the use of high efficiency class B push-pull amplifiers as the audio frequency modulators. 25:

It is a second object to provide means for performing syllable frequency modulation with high efficiency at high power with particular reference to syllable frequency plate modulation on the final stage of high frequency amplification of a transmitter. 30:

In accordance with one feature of the invention in a floating carrier transmitter in which a modulated thermionic valve device is plate modulated by both speech and syllable frequency voltages, speech frequency voltages are amplified by a 40: thermionic amplifier biased back to class B operation, before being impressed upon the modulated thermionic valve device. 35:

According to a further feature of the invention in a floating carrier transmitter in which a modulated thermionic valve device is plate modulated by syllable frequency voltages, the plate voltage supply source for the modulated valve device is adapted to be controlled by syllable frequency control voltages in such a manner that the voltage 50: supply varies in accordance with the mean amplitude level of speech frequency currents.

Referring now to the arrangement illustrated in Fig. 2, in this circuit the valves V₁ and V₂ are acting as modulated high frequency amplifiers in 55:

a push-pull circuit. The valves V_3 and V_4 are biased back to act as class B audio frequency amplifier valves working into transformer T_2 , the output of which is applied across the valves V_1 and V_2 . The operation of the circuit is briefly as follows:

The average current of a class B amplifier is proportional to the average amplitude of the current output. The plate current taken by the two valves V_3 and V_4 , which in this case is taken from the choke coil L_1 , is the sum of the plate current taken by V_3 and V_4 and its amplitude is related to the amplitude of the programme to the transmitter. Depending on the grid bias applied to these valves the total plate current will vary from a small value when no programme is transmitted to the full load value on full programme.

It is well known that when working in the condition for correct operation as a modulated amplifier, the effective impedance of the plate circuits of the modulated amplifier valves considered from the audio frequency viewpoint is that of a pure resistance. The voltage developed across the modulated amplifier is, therefore, directly proportional to the current taken by the modulator valves as in the arrangement shown the total plate current flows through the modulated amplifier and the modulator valves in series. It follows therefore that, if the circuit is so adjusted that the correct voltage for obtaining the full power output from the modulated amplifier valves, is developed across them when the modulator valves are taking their full load current, then when the modulator plate current falls to a low value corresponding to a low programme load, the modulated amplifier plate current and voltage will also fall to a low value and hence the total power consumption and power output are decreased.

It is possible by suitably varying the ratio of no modulation current to full modulation current in the modulator valves to vary over a wide range the ratio of full-modulation power to no modulation power ratio.

Experience shows that a ratio of the order of one to four between no modulation power and full modulation power is satisfactory for broadcasting services, although other power ratios can also be obtained.

As the efficiency and the impedance of the modulated amplifier remain constant, a change in the total plate current of one to two is required to obtain the above effect. Consequently, with a fixed total anode supply voltage and a condition on full load in which the total anode voltage is divided approximately equally between the modulator and the modulated amplifier, it is necessary that the impedance of the modulators should be three times greater on no modulation than on full modulation. With the modulator adjusted to give the correct efficiency on full modulation, this ratio may not be obtained with a fixed grid bias, as this ratio will depend partly upon the characteristics of the valves used. It is desirable therefore, that the grid potential of the modulator should be varied at syllable frequency so that the grid bias is correct for the average programme level at any instant. Referring to Fig. 1 this is accomplished by means of the rectifier 3 with its associated output resistance and condenser. A similar means may be used in connection with the arrangement of Fig. 2.

It is also possible to increase the power ratio between no modulation and full modulation by

suitably changing the modulator grid bias at syllable frequency.

The choke coil L_1 , in conjunction with the capacity C_2 , prevent modulation of the modulated amplifier directly by audio frequency variations in the total plate current of the modulator valves. C_1 is a by-pass condenser and C_3 is a blocking condenser inserted to prevent the plate to filament impedance of the modulated amplifier from being short-circuited for direct current by the secondary of the transformer.

The grid bias of the modulated amplifier valve may be obtained from a source of negative grid bias, such as generator or rectifier, or may be obtained by means of a grid leak connected back to its own filament.

A mercury vapour rectifier equipment furnished with grid control may be arranged so that the output voltage of the rectifier supplies the plate voltage of the modulated amplifier.

This method is illustrated in Fig. 3 in which 1 is a high frequency amplifier capable of being modulated by voltages impressed on the anodes; 2 is a high efficiency audio frequency modulator in the form of a Class B push-pull amplifier; 3 is a grid-controlled mercury vapour high tension supply rectifier unit connected to a constant A. C. source and supplying anode voltage to the modulated amplifier; 4' is a grid control unit which, according to methods already known, enables the high tension voltage from the rectifier to be varied by phase displacement of A. C. voltage applied to the grid, these phase displacements being regulated by unidirectional voltages fluctuating at syllable frequency voltages; 5 is a rectifier delivering unidirectional syllable frequency voltages resulting from rectification of audio frequency voltages impressed on its input terminals, and 6 is an anode voltage supply equipment for the modulator.

The manner of operation is briefly as follows. When no audio input voltage is being supplied, the plate voltage on the modulated amplifier, as furnished by the mercury vapour rectifier, is a certain fixed value and a certain fixed carrier power output is delivered by the modulated amplifier.

If a single frequency audio input is now applied at the speech input terminals, a D. C. voltage due to rectification of this tone will appear at the output of the syllable frequency rectifier 5. This D. C. voltage acting on the circuits in the control unit 4' results in a change of the plate voltage furnished by the mercury rectifier 3 to a new and higher value. This causes the carrier delivered by the modulated amplifier to change to a higher value. At the same time the higher carrier is modulated by the audio tone through the action of the modulator 2.

If speech or music is applied at the input terminals, the output from the rectifier 5 is a voltage varying at syllable frequency which, acting through the control unit 4', causes the plate voltage furnished by the rectifier 3 to vary at syllable frequency resulting in fluctuation of the carrier delivered by the modulated amplifier at syllable frequency. At the same time the fluctuating carrier is modulated by the speech or music.

The amount by which the carrier is caused to rise with modulation may be chosen arbitrarily. In broadcasting transmitters it is found satisfactory to arrange that the carrier amplitude corresponding to audio input resulting in 100% modulation should be about twice the amplitude existing when no audio input is applied. The

carrier amplitude varies linearly with the plate voltage on the modulated amplifier and, therefore, for a two to one ratio of amplitude the voltage of the mercury rectifier is doubled for the 5 audio input voltage giving full modulation.

The value of the floating carrier method lies in the saving of power effected by reducing the carrier power when modulation is light. In the 10 present case a reduction of the plate voltage on to the modulated amplifier in a two to one ratio results in a reduction of the power drawn from the mains by the mercury vapour rectifier in a four to one ratio approximately. This reduction is accompanied by a change in power factor from 15 about unity to about .5. When the power factor is low the current can be made to lead or lag as desired. In some cases, operation with leading current may be advantageous.

In the arrangement illustrated in Fig. 3 a separate 20 source of anode voltage is shown for the modulator. This is not essential and with suitable precautions the modulator might be fed from the same anode supply as the modulated amplifier.

25 The invention is not restricted to the precise arrangements described above and numerous other modifications may be made coming within the scope of the appended claims. For example the average plate current of a class B modulator 30 amplifier which fluctuates at syllable frequency following the mean level of audio frequency voltage may be used as the supply of syllable frequency voltage for operating on the grid of a mercury vapour rectifier supplying the modulated 35 amplifier. This enables a separate rectifier producing syllable frequency voltages to be dispensed with.

Such a system is represented in Fig. 4 which 40 essentially resembles the system of Fig. 3 except that the rectifier 5 for deriving syllable frequency voltages to control phase shift device 4' has been omitted and the phase shift device 4' is shown as being controlled directly by the average plate current of modulator 2.

45 What is claimed is:

1. In a floating carrier signalling system in which a carrier frequency wave is modulated by a source of signal frequency, a modulated thermionic tube device, a transmission channel 50 for applying signals from said source to said device, a controllable voltage supply source, connections from said voltage supply source to the plate circuit of said modulated thermionic tube device, amplifier means included in said transmission 55 channel for amplifying the signals from said source of signal frequency before application of said signals to said device, said amplifier means being biased so as to also produce a uni-directional voltage which varies in accordance with 60 the mean energy level of said source of signal frequency, connections for applying said ampli-

fied signals to the plate circuit of said device, and means for controlling said voltage supply source in accordance with said uni-directional voltage.

2. In a floating carrier signally system in which a carrier frequency wave is modulated by a source 5 of signal frequency, a modulated thermionic tube device, a source of signal frequency, means for impressing signals from said source of signal frequency upon said modulated tube device, a mercury vapour rectifier for supplying plate voltage to said modulated tube device, a grid control device for said mercury vapour rectifier, electron discharge tube means included in said means for impressing signals for amplifying said signals before impressing them on said modulated tube device, said electron discharge tube means being biased for class B operation whereby there is produced in the output of said electron discharge tube means an average plate current which varies in accordance with the mean level of said signal frequency voltage, and means for applying said variation in said average plate current to said grid control device.

3. In a floating carrier signally system in which a carrier frequency wave is modulated by a source 25 of signal frequency, a modulated thermionic tube device, a source of signal frequency, a thermionic tube amplifier biased to class B operation for amplifying said source of signal frequency, means for impressing said amplified source of signal 30 frequency upon said modulated tube device, an alternating current power source, a rectifier having a grid and connected to rectify current from said power source for supplying plate circuit of said modulated tube device, and means for using 35 the fluctuations in the average plate current of said class B amplifier for controlling said grid to vary the voltage supplied to said device from said rectifier in accordance with the mean energy level of said source of signal frequency.

4. In a floating carrier transmitting system a source of signals, a push-pull electron discharge amplifier biased for class B operation connected to amplify said signals and having a plate current circuit and an audio frequency output circuit 45 partially coinciding with said plate current circuit but distinct therefrom, a modulated thermionic device, an alternating current power source, a rectifier having a grid and connected to rectify current from said power source for supplying plate voltage to said device, coupling means connecting the output of said amplifier to said device, and separate connections between the plate current circuit of said amplifier and said grid for controlling the voltage supplied to 50 said device from said rectifier in accordance with the average current in the plate circuit of said amplifier.
